Thomas D. Tweedie, 2226 Fairgreen Ave.,
Monrovia, Calif. 91016

Filed Feb. 10, 1971, Ser. No. 114,409

Term of patent 14 years

Int. Cl. D3—01

U.S. Cl. D87—5 F

FIG. 1.

FIG. 2.

FIG. 3.

FIG. 1 is a side perspective view of a luggage case embodying my new design;

FIG. 2 is an end elevational view, the opposite end being a mirror image of the end shown; and

FIG. 3 is a side elevational view thereof showing the side opposite that seen in FIG. 1.

The surface shading on the side panels represents fabric which is continuous on the face of said panels.

I claim:

The ornamental design for a luggage case, as shown and described.
